Primary Examiner—Philip S. Hyder

Assistant Examiner—Selina Sikder

(**) Term: **14 Years**

(74) Attorney, Agent, or Firm—Brooks Kushman P.C.

(21) Appl. No.: **29/209,693**

(57) **CLAIM**

(22) Filed: **Jul. 20, 2004**

The ornamental design for a remote device, as shown and described.

Related U.S. Application Data

DESCRIPTION

(62) Division of application No. 29/182,609, filed on May 29, 2003, now Pat. No. Des. 493,149.

FIG. 1 is a perspective view of a remote device showing our new design;

(51) **LOC (8) Cl. 13-03**

FIG. 2 is a left side elevational view of FIG. 1, the right side being a mirror image thereof;

(52) **U.S. Cl. D13/168**

FIG. 3 is a top plan view of FIG. 1;

(58) **Field of Search** D10/104, 106;

FIG. 4 is front elevational view of FIG. 1; and,

D13/162, 168; D14/174, 218; 123/179.2;

FIG. 5 is a rear elevational view of FIG. 1.

340/825, 825.22, 825.25, 825.31, 825.58,

The broken lines are for illustrative purposes only and form no part of the claimed design.

825.69, 825.72; 341/176; 455/151.1, 151.4,

352
